UNITED STATES PATENT OFFICE

WILLIAM A. FLOWER, OF TWIN FALLS, IDAHO

PHOTOGRAPHIC-PRINTING MACHINE

Application filed February 18, 1927. Serial No. 169,253.

This invention relates to a machine for printing photographs from negatives, one of the objects being to provide a structure of this character the print supporting surface of which is arranged at such an angle as to allow the prints to be delivered by gravity after the printing operation, thereby greatly speeding up the quantity production of photographs.

10 A further object is to provide a film holding device which can be operated by a foot pedal, means being employed in connection with the platen of the machine for stamping each print when brought to proper position upon the negative.

With the foregoing and other objects in view which will appear as the description proceeds, the invention resides in the combination and arrangement of parts and in the 20 details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

25 Figure 1 is a side elevation of the printing machine.

Figure 2 is a plan view on an enlarged scale of the inclined face of the light box and the parts carried thereby.

Figure 3 is a section on line 3—3, Figure 2, 30 one position of the platen being shown by full lines and another position being indicated by broken lines.

Figure 4 is a section on line 4—4, Figure 2.

Figure 5 is a section on line 5—5, Figure 2.

40 Figure 6 is a section on line 6—6, Figure 2.

Figure 7 is a plan view of a portion of a modified form of the machine, the platen being broken away to show the form of film holder used.

45 Figure 8 is a section on line 8—8, Figure 7.

Figure 9 is a section through a portion of the film holder, said section being on the line 9—9, Figure 8.

50 Referring to the figures by characters of reference 1 designates a light box, the lamp

therein (not shown) being included in a circuit with a fixed contact 2 and a movable or spring contact 3 both of which are located on the inclined portion 4 of the top of the box. This inclined portion has an opening 5 55 therein covered by a glass light 6 the upper surface of which is flush with the corresponding surface of the box. Adjacent the upper side of the opening 5 is a guide strip 7 fixedly connected to the box and arranged on the box 60 adjacent one side of the opening 5 is a cross strip 8 which can be mounted at its ends on supporting blocks 9. A platen consisting of hingedly connected members 10 and 11 is adapted to extend over the opening 5, there 65 being a hinge leaf 12 projecting beyond one side edge of the platen and hingedly attached as at 13 to the strip 8. The lower or active face of each member of the platen is provided with a soft covering 14 of felt or the like and 70 an arm 15 is extended from the free side edge of the platen to a point where it can come into contact with the movable contact 3 so as to force it against the contact 2 when the platen is in normal or closed position. The 75 platen is adapted to be operated by means of a handle 16 and relative movement of the two members of the platen can be limited by a stop bracket 17 carried by one of the members.

Arranged on the inclined top of the light 80 box beneath the hinge leaf 12 and between the platen member 10 and the block 9 is a clamping strip 18 the ends of which are mounted in channeled guide brackets 19 secured to the light box. Springs 20 are seated 85 in recesses 21 in the clamping strip 18 adjacent the ends thereof and serve to hold said strip normally spaced a short distance from the inclined upper surface of the light box. A rod 22 is slidable within the top of the light 90 box and within each spring 20 and is connected to the upper surface of the strip 18. To each of these rods 22 is attached a cord 23 or the like, the said cords being in turn connected to a pull cord 24 mounted on a 95 guide sheave 25. The pull cord 24 is extended to a foot pedal 26. Obviously, therefore, when the pedal is shifted out of normal position the strip 18 will be pulled toward the top of the light box against the action of 100

the springs 20 so as to clamp upon a negative extending under the strip. To facilitate this clamping action a strip of any suitable material indicated at 27 can be fastened along that face of the clamping strip 18 nearest the opening 5, this strip 27 having a longitudinal flange 28 for bearing against the negative.

A bracket 29 is mounted on the member 10 of the platen close to one corner thereof nearest the hinge 13, said corner being cut away as shown at 30 so as to receive the lower end of an adjustable rubber stamp 31 or other suitable impression device. The impression device illustrated is supported at one side of the bracket 29 and is pivotally connected thereto. A link 32 is pivotally connected to the upper portion of the impression device and is slidably mounted in a bracket 33 mounted on the top of the light box. An ink pad 34 is arranged on the light box at a point where it will be engaged by the impression surface of the stamping or printing device when the platen is moved upwardly and laterally away from the opening 5 as shown by broken lines in Figure 3. The impression device is so located with reference to the hinge 13, however, that when the platen is moved to active position, the impression surface will contact with the back of a print supported beneath the platen.

A guide rod 35 is extended along two guides of the inclined portion of the top of the light box and parallel with two sides of the opening 5. On one portion of this rod is mounted an opaque mat 36 and another opaque mat 37 is mounted on another portion of the rod, the two mats being disposed at right angles to each other and crossed.

A counter indicated generally at 38 can be located on the light box near the opening 5, this counter being provided with the usual operating arm 35. A finger 40 extending from the platen is adapted to engage and depress arm 37 each time the platen is lowered to active position.

In practice the mats 36 and 37 are adjusted relative to each other to define an opening of the size of the picture to be printed. The platen is swung upwardly and laterally to expose the glass light 6. Thereafter the negative is inserted under the clamping strip 8 to position along the guide strip 7 and upon the mats 36 and 37. This negative has been indicated N in the drawing. The operator then depresses the pedal 26 which causes the negative to be clamped as heretofore explained. Thereafter the sensitized paper is placed on the negative and the platen moved downwardly to clamp the paper upon the negative. This movement of the platen will produce three operations, namely the printing of a designating number or the like on the back of the paper, the closing of the circuit through the contacts 2 and 3, and the actuation of the counter 38. The resultant illumination of

the light box will produce the desired printing of the photograph and thereafter the platen is raised to break the circuit, release the print, and reapply the impression device to the ink pad 34. By releasing strip 18 the gripped negative will be released and a new one can then be brought to position.

Instead of providing the film holding means illustrated in Figures 1 to 6 inclusive a modified structure such as illustrated in Figures 7, 8 and 9 may be employed. In this modified structure an angular film holder 41 is extended along the upper edge and one side edge of the opening 42 in the top 43 of the box, the upper portion of this holder being connected to the top 43 by hinges 44. Gripping tongues 45 are extended laterally from a strip 46 attached to the side portion of the film holder, these tongues being designed to engage and grip a film when properly placed under the holder. An arm 47 is secured to and extends from the side portion of the holder and has a projecting portion which is normally thrust upwardly by a spring 48 as shown particularly in Figure 8. An actuating cord 49 or the like can be connected to the arm 47 and extended downwardly through the top 43. By actuating this cord the arm 47 can be pulled downwardly so as to swing the film holder upwardly a short distance. Thus a film can readily be inserted under the holder. When the cord 49 is released the holder will move automatically into film engaging position so as to hold the film firmly.

Secured to the top 43 adjacent one end of the upper portion of the film holder 41 is a bracket 50 provided with an arm 51 parallel with the side of the opening 42. To this arm is secured the leaf 52 of a hinge, the other leaf of said hinge being attached to the platen 53 which can be of the same construction as the ones shown in Figures 1 to 6 inclusive. This platen can also be provided with the same marking means heretofore described the inking pad forming a part thereof being indicated at 54 and being mounted on the bracket 50. As the bracket arm 51 is elevated above the top 43 a clearance is left below the hinge leaf 52 so that the insertion and removal of a film will not be interfered with.

What is claimed is:

1. A photograph printing machine including a light box having an opening, means for supporting a negative across the opening, normally crossed mats hingedly and slidably connected to the light box for adjustment to a supported negative, a cross strip supported by but spaced from the light box adjacent the negative supporting means, a platen hingedly connected to the cross strip for clamping a negative to the supporting means and holding a sensitized sheet to the negative, there being a space between the light box and the cross strip for the reception of a negative slidably along the light box to position on the

supporting means, a yieldingly supported clamping member adjacent the cross strip and beneath the platen, and means actuated from beneath the light box for actuating the 5 clamping strip to bind the negative and hold it against movement relative to the light box.

2. A photograph printing machine including a light box having an opening, means for supporting a negative across the opening, normally crossed mats movably connected to the 10 light box for adjustment to a supported negative, a cross member supported by but spaced from the light box adjacent the negative supporting means, a platen movably mounted for clamping a negative to the supporting means 15 and holding a sensitized sheet to the negative, there being a space between the light box and said cross member for the reception of a negative slidable along the light box to position on 20 the supporting means, a yieldingly supported clamping member adjacent the cross member and beneath the platen, and means for actuating the clamping member to bind the negative and hold it against movement relative to 25 the light box.

In testimony that I claim the foregoing as my own, I have hereto affixed my signature.

WILLIAM A. FLOWER.
